2 Sheets-Sheet 2

Inventor:
Roy H. Robinson,

by Fisher, Towle, Clapp & Sons, 577tys

UNITED STATES PATENT OFFICE

ROY H. ROBINSON, OF CHICAGO, ILLINOIS

GOLF CLUB

Application filed April 22, 1926. Serial No. 103,773.

My invention relates to golf clubs and shafts therefor, or like game clubs, and has for its primary object to provide a practical, durable, and economical construction of great strength within the range of weight allowed therefor, and adapted to replace the wood and tubular metal constructions for shafts, with or without the wooden heads, and to overcome the objections to such constructions.

Further objects of the invention are to reduce the wind resistance; to provide a novel composite wire frame or truss reinforcement construction for golf clubs or shafts for use with or without plastic formation in which the same is embedded and with a separate or integral head; to provide increased strength in the shaft over the wooden or tubular metal shafts; to eliminate the use of wood, especially in the shaft, and the use of tubular metal, such as tapered steel tubing, as well as to permit a wide range of minute variations in the stiffness of flexibility of the shafts and shanks thereof to suit the most exacting desires or requirements of the different players of golfers; and in general to provide an improved article of the character described.

The many other objects and advantages will be better understood by reference to the following specification when considered in connection with the accompanying drawings illustrating certain selected embodiments of the invention, in which:

Fig. 1 is an elevation of a golf club embodying a plastic composite construction, the same being shown partly broken away and in section to more clearly illustrate the same.

Fig. 2 is an enlarged fragmentary sectional view showing a modified construction with a skeleton or open truss frame reinforcement and other features.

Fig. 3 is a fragmentary elevation partly broken away and in section to show another form of reinforcing construction.

Fig. 4 is a fragmentary elevation in which the construction shown in Fig. 1 is provided with a reinforcement.

Fig. 5 is an elevation, partly in section, of a golf club with a skeleton or open frame

shaft construction which may be employed with or without embedding the same in fibrous or plastic material.

Fig. 6 is a fragmentary sectional elevation showing another form of reinforcement.

Fig. 7 is a fragmentary sectional view showing a modified form of composite structure and reinforcement.

Fig. 8 is a sectional perspective view of a structure somewhat similar to that shown in Fig. 3.

Figs. 9 to 17 inclusive are transverse sections of modified forms of shaft construction and reinforcing means therefor, and

Fig. 18 is a fragmentary sectional view showing a modified construction for anchoring a shaft to the head of the club.

Heretofore, golf clubs have been constructed with wood or metal heads and with wood or tubular metal shafts in the form of tapered steel tubing. Considerable difficulty has been experienced for a number of years in securing suitable wood for the shafts which would not readily splinter or crack. In addition, wood has many limitations in strength and flexibility, as well as inability to stand up under the strains and rough usage to which the same is subjected in play, with the result that shafts are quite frequently broken and more or less result in lack of confidence in the player as to the ability of the wood to stand up in use. This has led to the construction of the shafts of tapered steel tubing, which, however, lack some of the essential characteristics of the wooden shafts in that certain qualities of flexing and torsioning or twisting, must be surrendered in providing the necessary stiffness to give the required strength in such tubular metal shafts. In addition, the cost of production is greater. In general, it is doubted if the tubular metal shafts are satisfactory and efficient owing to the absence of many qualities of the wooden shaft, such as the proper torsioning and flexibility, and in the case of wooden clubs as distinguished from irons, the ability of giving the proper "follow-through."

My present construction for golf clubs and particularly the shafts thereof, may be constructed to have all of the advantages of the

wooden shafts in addition to overcoming the disadvantages of both the wooden and tubular steel shafts and providing independent or integral heads and increased strength, as well as resulting in a club which can be given the required resiliency or flexibility to suit the most exacting requirements of different golfers and yet economically produced. One of the features of the improved golf club or shaft construction is the employment of a tough fibrous or plastic material of high tensile and compressive strength in addition to being light in weight, waterproof, and unaffected by the elements, or by hot water or such solvents as alcohol, acetone, benzine, turpentine, etc., in addition to having all of the good properties of vulcanized fiber, as well as being a nonconductor or dielectric. For this purpose, the molded material is preferably waterproof so as not to warp from climatic conditions and may be of Bakelite or, preferably, the combination of Bakelite with a fiber or textile base such as condensite-celoron, a product of phenol and formaldehyde, which may be described as a vulcanized fiber thoroughly impregnated with condensite and hardened by heating. This material has a tensile strength from 8800 to 11000 pounds per square inch and a compressive strength of from 26000 to 45000 pounds per square inch, but I desire to have it understood that any other suitable material possessing the same or necessary properties may be employed.

The shaft may be made of the skeleton or open truss frame construction which possesses great strength and can be produced with the required resiliency, flexibility, or torsional effect, in addition to reducing winding resistance in use, or using such truss frame reinforcement in a composite structure in which the same is embedded in some suitable plastic material or mastic such as bakelite, celoron-condensite, or fiber somewhat of the type above referred to, in which event the high tensile strength of the truss metal framing of steel wire or strips so embedded is supplemented by the high compression strength of the mastic or fibrous material supplemented by the relatively high tensile strength of the latter. The plastic material is preferably of that type having a vulcanized woven fabric base which is hydrolyzed to shrink the fabric into a dense mass which imparts to it the necessary strength, toughness, and resiliency characteristic of vulcanized fiber such as employed in the making of gears and which is of great durability and able to stand up under sudden shocks or strains. It is also pointed out that by using a skeleton or open truss frame construction which may be utilized alone or embedded as described, shafts with or without the head to be formed of the molded plastic fibrous material may be made of considerable greater strength and flexibility and with the desired

torsional qualities owing to the fact that steel wire or strips may be produced of considerably higher tensile strength and quality than is possible with metal tubing, especially tapered steel tubing which is employed in making golf shafts.

It is also to be understood that the celoron-condensite or other plastic fibrous material may be produced in tubular or solid form as shall be found desirable, while the framing or truss construction may be greatly varied as will be readily evident from the detailed description which follows, although it is to be understood that this description is merely illustrative of the principles involved.

Referring to the drawings in detail and particularly to Fig. 1, there is shown a shaft 19 of such plastic material as celoron-condensite tapering from its gripping portion 20 to the shank portion 21. This shaft may be of tubular form as indicated at 22 and joined to or formed with a head 23, the attachment of the separate head as is common in the art being optional to the integral formation of the head therewith, as illustrated. In either event, the shank 21 may be reinforced with a separate reinforcement rod or core 24, whether the shank be of solid or hollow formation, such reinforcement being of metal or other material which is tough, flexible, or pliable and of high tensile strength. For this purpose rawhide or cowhide may be used. As is shown in Fig. 1, the ends may be suitably anchored in the plastic material or embedded therein during the formation of the shaft, as by forming shoulders or enlargement 25 and 26 on the ends of the reinforcement or core about which the plastic material is formed or fitted in openings or recesses 27 and 28 provided for this purpose. The gripping portion 20 may be finished to suit the desires of different players in that it may be made with a roughened surface or finished off smooth and polished or wrapped with a suitable covering of leather or other material such as commonly used at the present time. In either case it may be desirable to form an enlargement or shoulder in the form of an annular bead or rib 29 at the upper end and a similar bead or rib 30 spaced therefrom at the lower limit or end of the gripping portion and also to prevent the club from slipping out of the hands of the player.

In the form of the invention shown in Fig. 2, the molded plastic body material of Bakelite, especially combined with fiber, celoron-condensite, or similar material is reinforced with a skeleton or truss frame 31, preferably comprising two or more openly spaced longitudinal 32 or wire or strips of higher tensile strength, such as steel, duraluminum, or the like, connected at spaced points along their lengths by transverse wire or strips forming struts or ties 33 to cause the longitudinals to

act together. These are embedded in the plastic material, the spacing and number of the struts and longitudinals depending on the stiffness or flexibility desired for different clubs. For instance, the truss frame for irons or similar clubs will be relatively stiff and those for what are ordinarily known as wooden clubs, such as drivers, brassies, and spoons, being relatively flexible. The truss 5 may taper toward the shank like the shaft, the longitudinals in this instance converging toward the shank 34 and head 35, which latter may be separate and of plastic material or wood, or integral as shown, where the head is 10 formed integral with the shaft and shank of plastic fibrous material. The reinforcing frame or truss especially the longitudinals 32, may extend into the neck and body of the head as shown in 36, this producing a monolithic construction. Also, a core or rod 37 15 of wire or other material may be provided to reinforce the shank or neck and head and the ends bent or turned over as at 38 to prevent slip or shifting of the body thereon or relative movement and secure effective bracing at the point where the greatest strength and flexibility are required.

Furthermore, in tubular shafts a central reinforce or core 39 may be provided secured 20 or joined to the inner wall. In order to keep within the range of weight allowed for the shafts, this core may be made of some light-weight and tough material which will permit the necessary pliability or flexing, such 25 as rawhide. In view of the fact that there are some weight limitations in golf shaft construction, the average shaft weighing between six and seven ounces, the tapered shaft of hollow or tubular construction with the 30 void or hollow center extending throughout the length of the shaft or down into the shank if desired, will keep the weight within the range allowed. Of course, the weight may be varied according to the desires of different 35 players and the core may extend down to the shank which from thereon can be solid as shown in Fig. 2 or made to contain a core of lighter material where weight permits as shown in Fig. 1. The core of rawhide may 40 be wound from a strip or produced from a solid piece shaped to fit.

In the construction shown in Figs. 3 and 5 the shaft is similarly provided with longitudinals 40 connected by transverse struts or 45 ties 41 which are slit at two points as indicated at 42 and the intermediate portions offset from the side portions to receive the longitudinals between such portions and through the slits, supplemented by securing 50 the same to the struts by welding, brazing, soldering, or otherwise, at the points of contact in the same manner that the struts 33 are connected to the longitudinals 32. The 55 golf shaft in this instance may be provided with tapered ribs 43 in alignment with the

longitudinals and tapering to a point at their lower ends, the longitudinals, if desired, projecting into these ribs. The truss frame may in this instance be supplemented by one or more spiral or helical windings 44 of wire or the like, a double spiral or helical winding being shown fixed in the body of the shaft or connected to the struts 41 to cause the reinforcement members to act together. In this form the core 45 is shown of solid or one-piece construction.

In the form shown in Fig. 4 the shaft 19 may be constructed with the ribs and truss reinforcement and either of tubular or solid formation and simply provided with the spiral windings or reinforcements 46 corresponding to the windings 44. In Fig. 6 the shaft 19 is of tubular formation and has a tubular core 47 reinforced by wrapping or windings 48 of spiral or other formation, which may be extended over the ends of pins 49, arranged at right angles to each other at suitably spaced points, the wires being anchored to these transverse pins or struts at the points of contact, if desired. As means for preventing the tubular core 47 from shifting relative to the tubular body of the shaft 19, one, such as the shaft, may be provided with annular ribs 50 extending inwardly to engage corresponding annular grooves 51 of the tubular core 47. This locks the two parts together and causes them to act as one when flexing or bending in use. It is, of course, understood that the wall of the tapered tubular shaft may be of uniform cross-section as shown in Figs. 1, 2, 3, and 6, or may taper in cross-section as shown in Fig. 7, in which instance the wall preferably increases in thickness toward the shank, where the greatest strength is required.

In Fig. 5 of the drawings the truss construction 31 is shown having the longitudinals 32 and the struts or ties 33 connecting the longitudinals, and, if desired, instead of embedding or encasing this truss frame in the plastic material, it may be left open, in which instance wind resistance in the swing of the club is considerably reduced. However, the gripping portion is tubular as indicated at 52 and may be provided with the annular beads or ribs 53 and 54 at the upper and lower ends thereof, while the handle portion may be wrapped in the customary manner, as shown. In this figure the head 55 is shown separate and may be of wood or plastic material reinforced with fiber, the truss frame 31 extending into the head through the neck portion 56 thereof and preferably reinforced with a tube 57 at the shank and neck in order to more securely anchor the lower end of the frame in the head and effectively tie the longitudinals together. This tube may be slit as indicated at 58 to provide anchoring means for the longitudinals or means whereby they can be connected

to the tube supplemented by spot-welding or the like as described in connection with the struts 41 in Fig. 3 of the drawings.

In Fig. 9 of the drawings the construction is the same as that shown in Fig. 6 except that the plastic body 19 is shown with the incorporated fiber or celoron-condensite with a vulcanized woven fabric base incorporated with the bakelite or plastic mass. In addition, this tubular shaft or body may be reinforced by two or more longitudinals 59, preferably four in number as shown, and the spiral or helical windings may be eliminated. In Fig. 10 the construction is the same as shown in Fig. 2 except that the struts or ties are constructed as shown in Fig. 3 of the drawings.

In Fig. 11 the shaft is shown reinforced with flat strips 60 which may be arranged radially or which may be of T-shaped cross-section having the head portions 61 arranged at right angles to the strips 60, conforming to and exposed on the outer surface of the shaft. In this form the tubular shaft or body is reinforced with a plurality of concentric cores 62 of rawhide or other light-weight and tough material which, although naturally pliable or flexible, may be stiffened as desired, in the same manner as the parts 24, 39, 45, and 47. In Fig. 12 the tubular shaft is shown reinforced with flat strips 63 fully embedded therein and connected by integral or attached struts 64. As shown, all of the struts or ties are made in the form of bands or wires.

In Fig. 13 the construction is the same as that disclosed in Figs. 3, 4 and 6, except that the core may be omitted and the longitudinals 65 of wire or steel rods simply connected by a single or double spiral coil or helix 66 which may be suitably connected or joined to the longitudinals and serve the purpose of struts.

In Fig. 14 the same construction is illustrated as in Fig. 13, except that the tubular shaft body has one or more windings 67 of textile fabric therein, such winding being arranged underneath or over the wire reinforcement or extended throughout the plastic embedded body and acting as ties and trussing between the major longitudinal reinforcement. This may be incorporated with either the longitudinals or the spiral windings, or both.

In Fig. 15 a shaft 68 of streamline cross-section is shown having a blunt or rounded front edge 69 and a tapered rear edge 70 reinforced by longitudinals 71 and 72 connected by struts 73. A plurality of the longitudinals or wires are preferably provided at the front or tension side of the shaft to give the desired tensile strength and flexibility in conjunction with the compressive strength of the mastic or plastic body. The forms described, of course, have the shafts tapered down to

form the shank in the usual way. Constructions of oppositely tapered formation are shown in Figs. 16 and 17, the shaft in this instance being designated at 74. In Fig. 16 longitudinals 75 and 76 are provided connected by strips or struts 77 extending across the central opening, while in Fig. 17 the longitudinals are shown connected by struts or ties 78 quite similar in plan view to the cross-section of the shaft.

Fig. 18 indicates a structure similar to that shown in Fig. 5 as employed for producing the shaft or truss reinforcement for the plastic body and for connecting the shaft to the head, except that in this instance the tube 57 is supplemented with a ferrule 79 secured to the tube and extending over the neck portion of the head in which the shank end of the open reinforcement or truss frame is anchored, the same as described in connection with Fig. 5.

A golf club or shaft constructed as above described will give greater tensile and compressive strength and may be constructed with minute variations in torsional strength and stiffness or flexibility so as to give the required whip where this is desired, or to give the required twist considered essential especially with such clubs as drivers. This is true in either the molded material, the metal shafts, or the shafts of molded plastic fibrous material reinforced with the open or truss frames or embedded high tensile steel wire or strips. The molded material being waterproof, it will not warp from climatic conditions, especially where Bakelite or preferably a combination of Bakelite with fiber or textile base known as celoron-condensite, a product of phenol or formaldehyde is used. The steel wires or strips may have a tensile strength up to above 200,000 pounds per square inch, but where desired on account of weight limitations, duraluminum or other high tensile strength aluminum alloy wires or strips may be employed or some non-metallic reinforcing material of sufficient tensile strength, such as rawhide strips which produce a light-weight tenacious core. Owing to the longitudinals being connected, the strains are transmitted to all of them and this applies where they are encased in the embedding material. Where the longitudinal ribs or ridges are provided on the shaft, the longitudinal reinforcements may extend into these ribs, thus spacing the longitudinals further apart and developing maximum strength by reason of spacing them as far from the center of the shaft as possible.

While I have shown and described my invention in a preferred form, I am aware that various modifications and changes may be made therein without departing from the principles of the invention, the scope of which may be determined by reference to the appended claims.

I claim as my invention:

1. In a golf club, a tubular plastic shaft of tapered formation, a reinforcing frame in the shaft and a head on the shaft, the reinforcements on the hitting front or tensile side being greater than on the opposite side.
- 5 2. A club shaft formed of plastic material of stream-line cross section and metallic reinforcements running longitudinally thereof, the reinforcements on the hitting front or tensile side being greater than that on the opposite side.
- 10 3. As a new article of manufacture, a club or like shaft formed of plastic material and having spaced metallic longitudinals embedded therein forming reinforcements, the reinforcements on the front side being greater than on the rear side.
- 15 4. In a golf club, a shaft composed of longitudinal metal reinforcements encased in a textile covering and combined in a hardened plastic molded body.
- 20 5. A golf club comprising a head having means of attachment to a shaft, and a shaft connected to said means of attachment and comprising high tensile wires, means for connecting said wires to each other, and a gripping portion thereon.
- 25 6. In a golf club, a head, and a tapered shaft of molded plastic material with reinforcements of high tensile wire embodied therein, the molded plastic material of the shaft being tubular for the major portion of its length and solid for a portion of its length adjacent its end of smaller outside diameter, said solid portion being of material length and extending from the tubular portion to the head.
- 30 7. A shaft as defined in claim 4 in combination with an integral molded head, the reinforcements of said shaft extending into and reinforcing said head.

ROY H. ROBINSON.
